UNITED STATES PATENT OFFICE.

HUGO GROSS, OF BROOKLYN, NEW YORK.

ELECTRIC-SWITCH CONTROL.

Application filed March 30, 1925. Serial No. 19,267.

This invention relates to a switch control device in general and particularly to the class commonly known as gang controls especially adapted for use in lighting of theatres and like places, where it becomes desirable to either simultaneously or individually close or open electric circuits, by which various lighting effects are attained.

Gang controls are generally known and in principle they consist of a plurality of switch control means connecting with individual switches of lighting circuits and controllable by a master switch control through common actuating means as for instance a shaft.

15 The individual switch controls in this case are pivotally mounted upon the shaft and may be operatively connected thereto at will.

20 One of the objects of my invention is to provide such individual switch control with independent and positively locking means whereby such control may either be caused to operate individually of the master control or in conjunction with that master control when the latter is moved into on or off positions, or to operate simultaneously with the master control when moved alternately into on or off positions.

25 The foregoing and further objects will be more fully apparent from the following description and the accompanying drawings, forming part of this disclosure, and in which:

Figure 1 is a front elevation of my device.

30 Figure 2 is a side elevation thereof, partially in section.

35 Figure 3 is an end elevation of an engaging member as it appears from looking from the right-hand side, and,

40 Figure 4 is a detailed view, partially in section, showing the detent operating device.

Referring to the drawings numeral 10 denotes a shaft or actuating means usually operated by a master control.

45 Pivottally mounted upon shaft 10 is the body of my individual switch control which is provided at its lower portion with a yoke 11, engaging the shaft. This yoke sits within bearings 12 formed at the end of extensions 13 of a bracket 14 which is attached to a panel 15. The bracket 14 has a central slot 16 corresponding with an opening 17 in the panel 15. Through this slot extends a connecting rod 18 from the control device to the switch operated thereby.

50 The connecting rod is pivoted as indicated at 19 and is capable of a reciprocating and

swinging motion imparted thereto by my switch control.

Arranged at both sides of bearings 12 there are two engaging members 20 and 21 60 securely fastened to shaft 10 by means of set screws 22. As will be seen these engaging members comprise cylindrical bodies with enlargements abutting with bearings 12 and provided with a recess indicated at 23, forming a tooth 24 which is adapted to engage detents 25 and 26 respectively. These detents are slidable rods guided within the body by lower guide lugs 27 and upper guide lugs 28 and are propelled in downward direction by compression spring 29. Mounted upon the inner frame 30 of the body is a double eccentric 31 pivoted at 32. This double eccentric is composed of two members 33 and 34, each provided with faces 35 varying in distance from pivotal point 32.

These faces 35 are adapted to engage a pin 36 protruding from the side of each detent 25 and 26. When the eccentric is moved into various positions, the detents will be either lifted or lowered depending which one of the faces of the eccentric engage the pins. In this manner the detents 25 and 26 will be brought either into or out of the operating range of the engaging members 20 and 21 or their respective teeth 24.

The outer shell 37 of the housing of my device is provided with a slot 38 having four recesses 39 adapted to be engaged by the selective handle 40 of the eccentric. These recesses permit the handle to be securely seated and arrested in its position to which it is adjusted.

As will be seen at the right-hand side of the housing, the various recesses are marked with Ind. meaning independent, on, off, and Pos. which means "in positive connection with the master handle." Thus when the handle 40 is brought into the position marked Ind. both detents 25 and 26 are lifted to clear the teeth 24 of the engaging members. In the on position detent 26 is lowered so it may be engaged by engaging member 20, while detent 25 is lifted above the engaging member 21. When handle 40 is set into off position, the positions of the detents are reversed. In the position marked Pos. both detents are permitted to come in the paths of engaging members 20 and 21.

It will be seen that these engaging members are set in reciprocal relation to each other, that is, engaging member 21 will op-

erate my device when the master switch is pushed in the direction towards panel 15 and engaging member 20 will cause the operation of my device when the master handle is pulled in the direction from panel 15.

The selective handle 40, attached to the eccentric 31, is reciprocating in its operation and is propelled by a spring towards the housing 37 of the device.

10 As will be seen in Figure 4 the handle comprises a stem 41, which is directly associated with the eccentric and upon which is slidably mounted a sleeve 42 permanently attached to knob 43, which is hollow. Bearing 15 against sleeve 42 is a spring 44 which is held in place by a washer 45 attached to stem 41 by screw 46. Sleeve 42 is adapted to engage the recess 39 provided in the slot 38 of the housing 37.

20 Attached to the inner frame 30 of the body is the main or operating handle 47 which is preferably marked by a colored washer 48 so as to distinguish the switch or the circuit operated by my control device. Handle 47 is 25 preferably screwed in from the top and is adapted to hold down the cover 49 of my device.

While I have described a specific construction of my device, be it understood that 30 changes and improvements may be made without departing from the broad scope of my invention for which I claim:—

1. In an electric switch control, adapted to be associated with actuating means operable by a master switch control, comprising a pair of engaging members fastened to said actuating member, a control body pivotally engaged the latter and disposed between said engaging members, a pair of detents associated with said control body and adapted to be engaged at will by said engaging members, means for simultaneously positioning said detents individually relative to said engaging members, and means for locking said positioning means in place.

2. In an electric switch control mounted with actuating means operated by a master switch control, a control body in pivotal engagement with said actuating means and 50 provided with an operating handle, a pair of engaging members fastened to said actuating

ing means, a pair of detents operatively associated with said body and adapted to be engaged by said engaging members when brought into their pass, means for individually but simultaneously positioning said detents relative to said engaging members, and spring propelled means for locking said positioning means in place when said detents are set.

3. In a switch control, a pivotally mounted body having means for swinging it into desired positions, a pair of detents operably associated with said body, a pair of detent engaging means arranged within the operating range of said detents but mounted independently of said body, means provided within said body for positioning said detents relative to said engaging means, and means for setting said positioning means in place.

4. A switch control, comprising a pivotal body provided with operating means, a plurality of spring controlled detents operatively mounted in said body, means associated with said body, but independent of said body operating means, for simultaneously positioning said detents, detent engaging means independent of said body but arranged within the operating range of said detents and 80 adjacent to said body and permanently attached to the pivot of said control body.

5. A switch control, comprising a body having an operating handle and pivotally mounted upon an operating shaft actuated by 85 a master control handle, a pair of spring controlled detents slidably mounted within and at the ends of said body, eccentric detent setting means disposed within the body and adapted to simultaneously position said detents, a pair of reciprocally designed detent engaging means fastened to said operating shaft at the sides of said body and within the operating range of said detents, a handle for actuating said detent setting means, and means for locking said actuating handle and thus said detent setting means in place.

Signed at New York in the county of New York and State of New York this 27th day of March A. D. 1925.

HUGO GROSS.
